K. N. HEALY

DOOR CONSTRUCTION FOR HOG HOUSES

Filed June 4, 1924

Patented Mar. 23, 1926.

1,578,028

UNITED STATES PATENT OFFICE.

KENNETH N. HEALY, OF RIVER FALLS, WISCONSIN.

DOOR CONSTRUCTION FOR HOG HOUSES.

Application filed June 4, 1924. Serial No. 717,860.

To all whom it may concern:

Be it known that I, KENNETH N. HEALY, a citizen of the United States, residing at River Falls, in the county of Pierce and State of Wisconsin, have invented certain new and useful Improvements in a Door Construction for Hog Houses, of which the following is a specification.

This invention relates to a new and useful improvement in door construction for hog houses, and has for its principal object to provide simple and efficient means for opening and closing the door.

A further object of the invention is to provide a door which is adapted for vertical sliding movement in opening or closing the door opening, guide means being provided for permitting the proper sliding movement of the door.

20 A further object of the invention is to provide a door construction for hog houses of the above mentioned character, which is simple in construction, inexpensive, strong and durable, and further well adapted for 25 the purposes for which it is designed.

Other objects and advantages of this invention will become apparent during the following detailed description.

In the accompanying drawing, forming 30 a part of this specification, and in which like numerals designate like parts throughout the same:

Figure 1 is a vertical sectional view of a hog house, showing the door in a closed 35 position.

Figure 2 is an inside elevation, showing the arrangement of the guide members and the guide means carried by the door.

Figure 3 is a transverse section, through 40 the door, showing the manner, in which the guide rollers co-operate with the guide rails, and

Figure 4 is a sectional view, taken approximately on the line 4—4 of Figure 2.

45 In the drawing, wherein for the purpose of illustration is shown the preferred embodiment of my invention, the numeral 1 designates a portion of a hog house, and the same includes the floor 2, the door opening 3, provided in the side 4, and the rafter 5. The door posts, which are provided on the inside of the side wall 4, adjacent the respective side edges of the door opening 3 are designated by the numerals 6 and 7 respectively.

Extending upwardly from the floor 2, on

each side of the door opening and being spaced from the door posts 6 and 7 are the tubular guide rails 8 and 9 respectively. The lower ends of the guide rails may be 60 embedded in the concrete floor 2, or may be otherwise supported in a secure position, and I do not wish to limit myself to any particular manner in which the lower ends of the guide rails are fastened. The upper 65 portions of the tubular guide rails, at points above the upper edge of the door opening 3, are inclined upwardly as illustrated at 10 and 11 respectively, in the drawings, and the upper ends of the inclined portions are disposed inwardly and are fastened to the 70 rafters 5, by any suitable fastening means, in the manner as illustrated, more clearly at 12 in the drawings. It is also apparent that the upwardly inclined portions 10 and 11 75 are spaced from the rafters 5, so as to permit the free sliding movement of the door 13.

For the purpose of bracing the intermediate portions of the tubular guide rails, I provide the bracing means, the construction of which is more clearly illustrated in Figure 4 of the drawing, and the same comprises substantially U-shaped members 14, one arm of each member 14 being of greater length than the other arm, and the longer arm being fastened at its outer end to one door post, in the manner as illustrated, at 15. The shorter arm 16 of each of the U-shaped bracing members has its outer end seatable in 80 a suitable opening provided in each of the guide rails, and if desired, a threaded connection may be provided between the shorter arms of the U-shaped bracing members and the tubular guide rails. The U-shaped bracing members are preferably arranged at the junction of the vertical portions of the tubular guide rails, and the inclined portions thereof, in the manner as clearly illustrated 85 in Figure 1 of the drawings.

The door 13 may be of any suitable construction, and the same is adapted for vertical slideable movement between the door posts 6 and 7 respectively. Extending 90 transversely across the upper portion of the door, on the inside thereof, is the shaft 17 and the same is journaled in suitable brackets 18, which extend from the side edges of the door, in the manner as clearly illustrated 95 in Figure 3.

The ends of the shafts 17 extend beyond the sides of the door and carry thereon the 100 105 110

rollers 19 and 20 respectively, the same being adapted for engagement with the guide rails 8 and 9, and also the inclined portions 10 and 11 of the guide rails. Extending 5 across the bottom of the door, on the inside thereof, and fastened thereto in any suitable manner is the guide rod 21, and the ends thereof extend beyond the sides of the door, and are bent rearwardly, as illustrated at 22, 10 for engagement with the tubular guide rails 8 and 9.

For the purpose of operating the door, so 15 that the same may be moved to either an open or closed position, I provide the actuating cable 22, one end of which is fastened to the upper edge of the door, as illustrated at 23, and the cable is adapted to extend around a suitable pulley 24, supported by the rafter 5, in the manner as clearly illustrated in Figure 1.

As shown in Figure 1 of the drawings, 20 the door 13 is in a closed position and covers the door opening 3. When it is desired to open the door, so that the hogs may pass 25 through the door opening, the free end of the cable 22 is actuated, and the door will be caused to move upwardly between the door posts, and as the door is raised, the 30 guide rollers 19 and 20, on the upper portion of the door will cooperate with the tubular guide rails, which are inclined at their upper portions, while the guide rod 21 on the lower end of the door will have its free 35 ends engaging the vertical portions 8 and 9 of the tubular guide rails, so that the door will be supported in proper position, when the same is operated. When the door has 40 been raised to uncover the door opening, and the door is in the position as shown in the dotted lines in Figure 1 of the drawing, the free end of the cable may be fastened to support the door in such position, at which time the ends of the rod 21 will engage the 45 U-shaped members 14 so as to limit the upward movement of the door.

The provision of a door construction of

the above mentioned character, for hog houses will enable the latter to be constructed at a very low cost, and will further obviate the necessity of having to provide side walls 50 of great height, such as is now done, and by constructing a hog house wherein the side walls are relatively low, the house may be kept warm in the winter weather and a more even temperature may be had, during 55 the warm weather. The simplicity of my device enables the same to be easily and efficiently operated, and will further be strong and durable, as well as inexpensive.

While I have shown the preferred embodiment of my invention, it is to be understood that various changes in the size, shape, and arrangement of parts may be resorted to, without departing from the spirit of the invention, and the scope of the appended 60 claim.

Having thus described my invention, what I claim is:

In combination with a building structure 70 provided at its side wall with a door opening and having a roof disposed in an inclined position above the door opening, a door structure including guide rails extending vertically along the side wall of the building and being disposed parallel with 75 the side wall from points below the lower edge of the door opening to points above the upper edge thereof, the upper portion of the guide rails being extended under the roof and approximately parallel with the 80 same, bracing members for the guide rails adjacent the juncture of the upper portions thereof with the lower portions, a door panel having at its lower edge guides which 85 engage the rails, rollers journaled on the upper edge of the door panel for engaging the rails, and means for raising the door to an open position at which time the guides engage the bracing members.

In testimony whereof I affix my signature.

KENNETH HEALY.
